(57) **CLAIM**

The ornamental design for a face down pillow, as shown and described.

DESCRIPTION

FIG. 1 is a perspective view of the face down pillow showing my new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof; and,

FIG. 9 is a perspective view thereof when the square portions are detached from the main body of the face down pillow.

The broken lines and the areas within them in the drawings depict portions of the face down pillow that form no part of the claimed design.

1 Claim, 9 Drawing Sheets
